UNITED STATES PATENT OFFICE.

JOHN J. SULLIVAN, OF IPSWICH, MASSACHUSETTS, ASSIGNOR TO THE SINGER MANUFACTURING COMPANY, A CORPORATION OF NEW JERSEY.

THREAD-CUTTING DEVICE.

1,066,862.

Specification of Letters Patent.

Patented July 8, 1913.

Application filed October 5, 1911. Serial No. 652,934.

To all whom it may concern:

Be it known that I, JOHN J. SULLIVAN, a citizen of the United States, residing at Ipswich, in the county of Essex and State 5 of Massachusetts, have invented certain new and useful Improvements in Thread-Cutting Devices, of which the following is a specification, reference being had therein to the accompanying drawings.

10 This invention relates more particularly to an improvement in that class of rotary work-clamps for buttonhole sewing machines forming the subject of the United States patent to J. G. Greene No. 319,700, 15 of June 9, 1885, and it has for its object to provide a simple and effective thread-severing and holding device adapted to be operated at the completion of a buttonhole stitching operation to sever the needle-thread and 20 hold the cut end thereof leading to the needle in readiness for beginning the succeeding stitching operation.

The invention consists essentially in providing one of the independently sustained 25 feet of the upper work-clamping member with relatively fixed and spaced thread-nipping and severing jaws at its inner edge and in interposing between such jaws a transversely reciprocating slide-plate having 30 thread-nipping and severing shoulders movable into and out of operative relation with the fixed jaws, means being provided for reciprocating said slide-plates to engage the needle-thread extending from the final stitch 35 of a buttonhole to the eye of the needle and for drawing the same between said jaws whereby the thread is nipped between the upper face of the slide-plate and the fixed 40 nipping jaw and is thereafter severed between the lower face of the slide-plate and the fixed severing jaw whose operative edge is arranged slightly rearward of the nipping jaw. The slide-plate preferably has a 45 loose connection with a spring operating lever fulcrumed upon the lower clamp member independently of the pivotal connection of the upper clamp member therewith but adapted to follow the closing and opening 50 movements of the upper clamp member for clamping and releasing the work.

The invention will be understood by reference to the accompanying drawings, in which—

Figure 1 is a perspective view of a button-hole clamp provided with the present im-

provement, and Fig. 2 an enlarged sectional plan view of the part thereof provided with the nipping and cutting devices. Fig. 3 is a front end elevation of the clamping foot provided with the nipping and cutting members, and showing its method of operation in connection with a stitched buttonhole, and Fig. 4 is a perspective view of the cutter-plate detached.

The work-clamp herein shown is of the 65 type commonly employed in the wellknown Singer rotary-clamp buttonhole machine, constructed substantially as represented in the United States patents to J. G. Greene Nos. 360,433, 360,434 and 360,435, dated 70 April 5, 1887. It is constructed with a base-plate 1 formed with the needle aperture or slot 2 whose walls embrace the needle-throat or button of the machine by which the clamp is guided in its travel in conjunction with 75 the usual depending guide-pin (not shown).

The base-plate 1 is provided with the gibs 3 to which are fitted the reduced extremities of the laterally movable clamp-plates 4 affording the lower work-clamping jaws, the 80 plates 4 being provided at the rearward ends with the fulcrum-blocks 5 formed with rearwardly extending ears 6 receiving the fulcrum-pins 7 for the tilting blocks 8 to which are secured the independently movable 85 spring arms 9 of the upper clamp member to whose outer ends are pivotally connected by means of the pins 10 the clamping feet 11 and 12. Intermediate their ends the upper clamp arms 9 are embraced by the slotted 90 cross-bar 13 of a link 14 whose lower end embraces a crank 15 of a transverse shaft 16 fulcrumed in the fulcrum-blocks 5 and provided with the finger-lever 17 for operating 95 the same to clamp and unclamp the work.

The adjacent edges of the clamping feet 11 and 12 are recessed in the usual manner to afford an intermediate needle aperture to expose the face of the work receiving the overseam stitches of the buttonhole.

The clamping foot 12 is provided in its inner edge with a longitudinal slot 18 substantially parallel with its operative face so as to form above the same a rigid thread-nipping jaw 19 whose operative edge is disposed in substantial alinement with the adjacent edge of the foot 12, and a rigid lower jaw spaced therefrom and beveled in its outer portion to form a sharp edge at its intersection with the lower face of the foot 110

and to afford an obtuse-angled thread-severing shoulder 20 disposed somewhat beyond the operative edge of the nipping jaw, as represented in Fig. 3.

5 The foot 12 has in register with the slot 18 and also disposed substantially parallel with the operative face thereof a transverse slideway 21 to which is fitted the sliding cutter plate 22 formed with a laterally projecting head 23 presenting at its upper and lower faces in opposition to the fixed nipping and severing shoulders 19 and 20 the coöperating movable shoulders 24 and 25. The operative end portion of the slide-plate 10 22 is preferably formed with a slit 26 parallel with its upper and lower faces to adapt the shoulders 24 and 25 to yield slightly in their engagement with the needle-thread to prevent the crushing of the thread 15 20 interposed between the shoulders 19 and 24. The nipping and severing shoulders 19 and 20 are so designated to indicate their respective functions in conjunction with the shoulders 24 and 25 of the slide-plate 22 which, in 25 practice, have the usual respectively blunt and sharp edges; the elements 20 and 25 being designed to coöperate in the severing operation to successively pinch and tear the thread which is firmly connected on opposite 30 sides thereof by the nipping elements 19 and 24 on the one hand and the work still gripped by the clamp on the other. In case the thread should not actually be severed by such means, the lateral shifting of the work 35 after opening the clamp will bring the thread into contact with the sharp edge of the jaw 20 by means of which the still taut thread will be cut off close to the work.

The slide-plate 22 has swiveled in its rearward end the eye 27 which embraces the operating lever 28 which is shown with its outer end bent into an eye 29, with a portion near its opposite end flattened and bent into a U-shaped spring 30 and having at its extremity the fulcrum-pin 31 disposed transversely to the body portion and fitted within a correspondingly arranged bearing aperture 32 in the fulcrum-block 5 beneath and parallel with the clamp-arm actuating rock-shaft 16. The operating lever, constructed and arranged as described, is enabled to swing vertically to follow the opening and closing movements of the upper clamp member and to yield laterally from initial outer position (represented in dotted lines in Fig. 1) to inner thread-engaging position substantially as represented in full lines in said figure, the swiveled eye 27 affording a loose connection between the same and the slide-plate 22 compensating for changes in angular relation of the parts thus connected in the operation of the nipping and severing device.

In the operation of the device, the material ⁶⁵ m is interposed between the upper and

lower clamping members and the clamp closed thereon, after which the machine is set in motion and the series of covering stitches s is applied in the usual manner, the work-clamp being given a semi-rotation in 70 stitching the eye of the buttonhole. At the completion of the stitching operation, and after the machine comes to rest, the needle-thread leads upwardly from the last stitch to the eye of the needle n, as represented in 75 Fig. 1. Before the position of the clamp is disturbed, and while the material is still held therein, the lever 28 is drawn inwardly by the operator to move the head of the slide-plate 22 inwardly partially across the 80 needle aperture so as to bring its shoulders 24 and 25 beyond the taut needle-thread, the rounded portion 23^x of the head serving to thrust aside the needle-thread which snaps in behind its operative shoulders, as represented in Fig. 1. Upon the release of the lever by the operator, it swings outwardly into the dotted line position of Fig. 1, carrying with it the slide-plate 22 which assumes the position represented in Fig. 3.

In the receding or operative movement of the slide-plate 22, the shoulder 24 first carries the needle-thread into operative engagement with the fixed shoulder 19 to nip the same, after which the continued receding 95 movement progressively draws in the portion of the thread between such point and the work to firmly clamp the same until the portion of thread thus tightened is brought into engagement with the severing shoulder 100 20 by which it is parted close to the work so as to leave a very short end attached thereto, the loose end leading to the needle being held nipped while the clamp is turned into initial position and opened for replacement 105 or shifting of the material for a succeeding operation, the thread end being still held in the nipper after the closing of the clamp to insure the proper formation of the initial stitch of a succeeding buttonhole.

From the foregoing description, it will be seen that the present improvement is not limited to the precise constructive features herein shown and described nor to application to the particular form of work-clamp above referred to, it being adapted for employment with other forms of work-holding members, as for instance the presser-foot of a straight-away sewing machine, the thread-engaging parts and their operating means being designed accordingly.

Having thus set forth the nature of the invention, what I claim herein is:—

1. A work-clamp comprising a clamping foot having at one edge spaced jaws intermediate which and disposed substantially parallel with the operative face of the foot is a guideway, a slide-plate fitted to said guideway and having a lateral extension affording thread-nipping and -severing shoul.

- ders acting in conjunction with said jaws, an operating lever fulcrumed upon said clamp, and a pivotal connection between said lever and slide-plate.
- 5 2. The combination with a work-clamp constructed with a lower clamping member and an upper clamping member pivotally connected therewith and provided with a needle-aperture and with a guideway connected with said aperture to form at the intersection therewith spaced thread-nipping and -severing jaws, a reciprocating cutter-plate fitted to the guideway and provided with thread-engaging shoulders acting in conjunction with said spaced jaws and movable into the needle-aperture, an operating lever fulcrumed upon said clamp, and a pivotal connection between said lever and cutter-plate.
- 10 3. The combination with a work-clamp constructed with separable upper and lower clamping members the former of which is provided with a needle-aperture, of spaced thread-nipping and severing jaws carried by the upper clamping member and a sharp cutting edge below the severing jaw at substantially the level of the work-engaging face of said member, a reciprocating cutter-plate provided with thread-engaging shoulders acting in conjunction with and movable between said spaced jaws and into the needle-aperture, and means sustained by said clamp for actuating said cutter-plate.
- 15 4. The combination with a work-clamp constructed with a lower clamping member and an upper clamping member pivotally connected therewith and provided with a needle aperture, of spaced thread-nipping and -severing jaws carried by the upper clamping member, a reciprocating cutter-plate slidingly fitted within the upper clamping member and provided with thread-engaging shoulders acting in conjunction with and movable between said spaced jaws and into the needle aperture, an operating lever fulcrumed upon the lower clamping member independently of the upper clamping member, and an operative connection between said lever and the cutter-plate.
- 20 5. The combination with a work-clamp constructed with a lower clamping member provided with a fulcrum-block and an upper clamping member pivotally mounted upon said fulcrum-block and provided with a needle aperture, of spaced thread-nipping and -severing jaws carried by the upper clamping member at one side of said aperture, a reciprocating cutter-plate slidingly fitted within the upper clamping member and provided with thread-engaging shoulders acting in conjunction with and movable between said spaced jaws and into the needle aperture, and an operating lever operatively connected with said cutter-plate and formed with a transversely extending fulcrum-pin journaled in the fulcrum-block of said lower clamping member and having intermediate said fulcrum-pin and its connection with the cutter-plate a resilient portion adapted to maintain the lever yieldingly in an initial position.
- 25 In testimony whereof, I have signed my name to this specification, in the presence of two subscribing witnesses.
